United States Patent Office.

WILLIAM HAMER, OF LITTLE LEVER, NEAR BOLTON, ENGLAND.

Letters Patent No. 69,658, dated October 8, 1867.

IMPROVEMENT IN SLIVER-CANS FOR COTTON, &c.

The Schedule referred to in these Letters Patent and making part of the same.

TO ALL WHOM IT MAY CONCERN:

Be it known that I, WILLIAM HAMER, of Little Lever, near Bolton, in the county of Lancaster, England, have invented a new and improved Apparatus Employed in the Preparation of Cotton and other Fibrous Materials; and I do hereby declare that the following is a full, clear, and exact description thereof, which will enable others skilled in the art to make and use the same, reference being had to the accompanying drawings, forming part of this specification, in which—

Figure 1 is a vertical section of a can, having in it a plate and spiral spring, for assisting the removal of the sliver.

Figure 2, a plan of the bottom of the can.

Figure 3, a plan of the movable plate only.

Similar letters of reference indicate corresponding parts.

This invention relates to the removal of the sliver from the can or coiler, and consists in placing underneath the material a spring of metal, so that, as the sliver is removed from the top of the can or coiler, its lower portion is raised upwards by the spring, and thereby prevents breakage.

In fig. 1 the can is shown at *a*, the plate at *b*, and the spiral spring at *c*. In fig. 2, *d* represents a hole in the bottom of the can, for admitting air during the removal of the sliver; and in fig. 3 the plate is shown detached. The spring of metal is formed of round, square, or other shaped wires, and is made of any number of coils, according to the size of the can and weight of material, and is applied to cans or coilers of all descriptions and purposes.

When the sliver is drawn up in the usual manner, it frequently becomes uneven, stretched, torn, or broken; but the application of my improved spring and plate causes the sliver to be gradually raised up from the bottom to near the top of the delivery, and, by taking off the strain, enables the sliver to be made as fine as possible, and prevents defects or breakage when leaving the can.

By the employment of my improved spring and plate the cans may be deeper and larger in diameter than usual, and thereby hold more material; they also require less tending and shifting, and have less wear and tear. Another advantage is that the pressure upon the sliver is commenced soon after it has begun to enter the can, and thereby enables it to be laid even and regular.

Having now described the nature and particulars of my said invention, and the manner in which the same is to be performed, I claim as my invention, and desire to secure by Letters Patent—

The spiral spring *c*, supporting the movable metal plate *b* in the can *a*, having the perforated bottom, all constructed and operating as described, for the purpose specified.

The above specification of my invention signed by me this fifth day of March, 1867.

WILLIAM HAMER.
